[57] CLAIM

The ornamental design for an overhead console, as shown
and described.

DESCRIPTION

FIG. 1 is an isometric view of an overhead console constructed
in accordance with the present invention;
FIG. 2 is a bottom view of the overhead console shown in
FIG. 1;

FIG. 3 is a left-side view of the overhead console shown in
FIG. 1, the right-side view being a mirror image thereof;
FIG. 4 is a front view of the overhead console shown in FIG.
1; and,

FIG. 5 is a rear view of the overhead console in FIG. 1.
